 2 Claims. (Cl. 18—8)

This invention relates in general to the production of artificial yarn and more particularly to an improved apparatus for the high speed extrusion of viscose yarn by the tube-spinning system.

It is known that a high tenacity viscose yarn can be produced if regeneration of the viscose is retarded by means of a chemical retardant such as hexamethylene-diamine, mon-isopropanol, etc., which retardants may be added either to the viscose spinning solution or to the spinbath into which the viscose is extruded, or to both. Although viscose spun by the use of one of these retardants ultimately produces a higher quality yarn than heretofore known, this yarn is extremely tender in the early stages of regeneration and must not be subjected to excess tension or abrupt treatment in the spinbath. Accordingly, first experiments in the use of retardants necessitated a reduction in spinning speed in order to prevent adverse effect on the yarn by turbulence created in the spinbath. This, of course, was undesirable from an economical standpoint since a given spinning machine would produce less yarn than before in a given period of time.

Subsequent to the aforesaid early experiments, it was found that the spinning speed could be increased substantially without deleteriously affecting the tenacity and quality of the yarn produced by the retardants, if the yarn were spun into and passed through a confined liquid treating zone, such as the two-diameter elongated spinning chamber or tube shown in copending application Serial No. 556,256, filed December 29, 1955, now Patent No. 2,908,937, dated October 29, 1959, which is owned in common herewith. In that application yarn is extruded from a spinneret into the small diameter portion of the tube, after which it passes into the large diameter portion, around suitable guide rollers and to a draw godet. The spinneret, two-diameter tube and first guide roller are submerged in a relatively large spinbath containing sulphuric acid and a small percentage of a chemical retardant.

During normal operation of the above described apparatus, yarn drawn through the two-diameter tube from the spinneret by the draw godet exerts a frictional pumping force in the direction of yarn travel on the liquid contained within the large portion of the tube, which creates a sucking action on the liquid in the small portion, resulting in a continuous flow of liquid from the spinbath through the tube in response to travel of the yarn therethrough. The flow speed of the liquid is dependent upon the speed of the yarn and the size of the tube through which the yarn and liquid travel. This process subjects the yarn to very little tensional force in the early and critical stages of regeneration and produces high tenacity yarn at high spinning speed since, when operating under proper conditions, the liquid flow assists rather than impedes travel of the yarn through the tube. It has now been found, however, that the foregoing process can be improved still further by practice of the invention which is to be described in detail hereinbelow.

Accordingly, an object of the present invention is to provide an improved apparatus for producing viscose yarn by the tube-spinning process.

A further object of the present invention is to provide

2

an improved apparatus for producing high tenacity viscose yarn.

Still another object of this invention is to provide an improved apparatus for producing high quality viscose yarn at high spinning speeds.

Another object of this invention is to provide a novel apparatus for deflecting a running length of freshly extruded yarn from a spinbath solution or regenerating liquid flowing in the same direction as that of the yarn with a minimum of turbulence.

An additional object of this invention is to provide a novel means for positioning the tube of a tube-spinning machine with respect to the spinneret of that machine.

A further object of this invention is to provide a novel apparatus adaptable for use in the tube-spinning of viscose yarn for uniformly dispersing liquid discharging from the tube and for preventing the formation of foam.

The objects of the present invention may be accomplished by extruding a viscose solution through a spinneret 20 which is submerged in a spinning tank containing sulphuric acid, drawing the freshly spun yarn and a stream of the acid bath in co-current direction through a confined treating zone or tube, removing a portion of the bath from the flowing stream at a point outside the spinning tank and thereafter separating the partially regenerated yarn from the flowing stream of remaining acid bath. One end of the tube is positioned adjacent to and in alignment with the face of the spinneret whereas the other end of this tube extends outside the spinning tank 25 into a separate compartment, hereinafter referred to as a chimney. Within the chimney and in alignment with the tube there may be mounted a tube extension, which extension supports a thread guide means, such as a freely rotatable guide or deflector roller. The extension and 30 roller serve as a means for separating the freshly extruded yarn from the acid bath while subjecting the yarn to the least possible turbulence and only slight tensional force due to frictional drag of the acid on the yarn.

These and further objects and advantages of this invention 40 will become apparent upon study of the following detailed description taken in conjunction with the annexed drawings, wherein:

FIGURE 1 is an elevational view, partially in section along the lines 1—1 of FIGURE 2, illustrating one spinning 45 unit of a spinning machine modified in accordance with the teachings of the present invention and showing conventional structure only when such is considered essential to a complete understanding of this disclosure;

FIGURE 2 is a plan view of the apparatus shown in 50 FIGURE 1, taken along the lines 2—2 of that figure; and

FIGURE 3 is an isometric view of the tube extension per se.

Referring now to the drawings, which show a preferred embodiment of this invention, and particularly to FIGURE 1, reference numeral 10 designates the upper portion of a spinning tank which contains the main supply of spinbath 11. This tank may be supported from the floor of the spinning room by any suitable means (not shown), and the longitudinal axis thereof extends generally horizontally, as shown. Within spinning tank 10 there is positioned a spinneret 12, an inclined two-diameter tube 13 and a chimney 14. The spinneret 12 and small diameter portion 15 of tube 13 are removably held in spaced but aligned position by supporting bracket 16 which is secured to the bottom plate of the tank, as can be seen from the drawing. The large diameter portion 17 of tube 13 extends into and is removably supported within one wall of chimney 14 by a sealing ring 18 constructed from rubber or any other elastic material which is not affected by the acid contained in spinbath 11.

A viscose solution is pumped to spinneret 12 from a

candle filter (not shown) through viscose supply line 20. The filaments extruded from the spinneret are threaded into and through the two-diameter tube 13 in a manner to be explained more fully hereinafter.

As shown in FIGURE 2, the chimney 14, into which the large diameter portion of tube 13 discharges both freshly spun yarn and a portion of spinbath 11, consists essentially of a vertical compartment defined on three sides by front wall 21, side wall 22 and rear wall 23, respectively, which structure resembles generally a channel beam, and on the fourth side by wall 24 of spinning tank 10. Chimney 14 is supported by flanges 25 which extend laterally from the bottom thereof and which rest on the upper surface of spinning tank bottom plate 26. In order to prevent flow of spinbath 11 into chimney 14 except through tube 13, the exposed longitudinal edges of both walls 21 and 23 are sealed to the spinning tank wall 24, and the flanges 25 are sealed to the bottom plate 26, as illustrated in FIGURES 1 and 2.

An opening 27 is cut or otherwise formed in the bottom plate 26 of tank 10. This opening, which is vertically aligned with the compartment defined by walls 21, 22, 23 and 24, permits flow of the spent or weakened spinbath downwardly in the direction of the arrow into a gutter (not shown) which directs flow of the bath to a recirculation zone (also not shown). In this zone, fresh make-up acid is added to and mixed with the weakened spinbath and the composite solution is fed under pressure to a supply acid trough and then to the spinning tank 10 through ports 28, as indicated by arrows in FIGURE 1. In this manner that portion of the spinbath which is pumped through tube 13 and weakened by exposure to the freshly extruded filaments is reclaimed and eventually recirculated.

Fixed within chimney 14 and in parallel or spaced alignment with the longitudinal axis of tube 13 is a tube extension indicated generally by reference numeral 30. This extension consists in ledges 31 and 32 which extend substantially parallel one to the other and which define a trough 33 therebetween, as can be seen in FIGURE 3. The trough 33 is of semi-circular cross-section and of a diameter slightly larger than the outer diameter of tube portion 17. This trough, in cooperation with the opening in chimney wall 23 and the ring 18, forms a cradle into which the discharge end of tube 13 is snugly but removably positioned.

In order to accurately position the tube 13 with respect to the tube extension and also with respect to the spinneret 12, a projection 34 is formed in the bottom surface of trough 33. This projection serves as a stop and limits movement of the tube in a forward direction, or in the direction of yarn travel, as can be seen in FIGURE 1 of the drawings. Inasmuch as the yarn and a stream of the spinbath solution flow through the tube 13 in a direction toward the tube extension, the tendency of this movement is continuously to urge the tube into engagement with the projection 34.

One end of a stub shaft 35 is fixed to the upper surface of ledge 31 adjacent to the discharge end thereof and projects inwardly and upwardly at an angle therefrom into general vertical alignment with the trough 33. Shaft 35 as shown forms a bearing surface on which guide roller 36 is rotatably mounted although it is obvious that this shaft could be utilized as a guide bar capable of deflecting the yarn. The guide roller is circumferentially grooved in a manner known to the art and deflects the yarn issuing from the tube and trough to a substantially vertical direction of travel, as shown in FIGURE 1, which of course separates the yarn from the moving body of regenerating solution. The groove apex on the lower side of roller 36 is in alignment with the longitudinal axis of tube 13 and serves to position the yarn centrally of the tube and trough. The yarn path and longitudinal axis of tube 13 extend slightly above the upper surface of ledge 31 at the discharge end of the tube. This allows excess

liquid discharging from the tube to spill out of trough 33, which reduces the turbulence around the filaments between the outlet end of the tube and the deflector roller 36 and consequently prevents breakage and wrapping of individual filaments around this roller. It is to be noted, however, that a sufficient amount of liquid flows to the end of the trough 33 to maintain the yarn submerged in the surface layer thereof until it is deflected by roller 36.

Tube extension 30 further comprises and has formed 10 unitarily therewith a wedge-shaped baffle plate 37 which extends laterally from ledge 31 and longitudinally from the discharge end of trough 33. When the tube extension is mounted within chimney 14, the baffle plate serves to support trough 33 in the chimney and also to seal a portion 15 of the upper extremity thereof. The baffle plate does not extend to wall 21, however, but is designed to define an opening 38 through which the weakened spinbath discharging from trough 33 may flow.

In order to expedite mounting of the necessary number 20 of spinning units in a conventional spinning machine, tube 13 and chimney 14 are angularly disposed with respect to the vertical plane of spinning tank wall 24, as can be seen in FIGURE 2. Moreover, the tube 13 and tube extension 30 are disposed at an angle of approximately 4 25 degrees with respect to a horizontal plane, as can be seen in FIGURE 1. This angular disposition ensures submersion of the spinneret 12 and entrance end of tube 13 an amount necessary to prevent a vortex of the spinbath which would pull air into the tube and therefore create undesirable turbulence. The discharge end of tube 13 is positioned sufficiently below the surface of spinbath 11 to ensure a uniform flow with a minimum of turbulence. The inclination of the tube also expedites discharge of 30 carbon disulfide liberated from the spinbath upon contact 35 of the same with the freshly extruded yarn, which also tends to reduce turbulence in the spinbath. Godet 40, which is driven in a known manner, draws yarn from the spinneret 12, through tube 13 and around guide roller 36, this action also serving to pump spinbath through the 40 tube as explained earlier.

Baffle plate 37 extends downwardly at an angle of approximately 15 degrees with respect to the longitudinal axis of trough 33 and serves not only to uniformly disperse the liquid emerging from the trough but also to prevent the formation and rise of foam in the chimney. 45

The spinning tank, chimney, tube extension and tube 50 supporting bracket may be constructed from lead or any other acid-resistant material and the tube 13 may be constructed from Pyrex glass. The flanges 25 of chimney 14 and tube extension 30 may be burned into position in a manner known to the art. The stub shaft 35 may also be burned into position within trough 33.

Example

Alkali cellulose prepared in a known manner was reacted with 34.4% carbon disulfide. The resulting xanthate was dissolved in a sodium hydroxide solution to produce viscose having the composition of 7.75% cellulose and 5.53% sodium hydroxide. This solution was modified by adding a chemical retardant. The spinning viscosity of 20° C. was 57 seconds (ball-fall) and the viscose had a xanthate ratio of .46.

The viscose solution prepared in the manner described above was spun into 1650/720 filament yarn by extruding through a spinneret into a coagulating and regenerating bath containing 6.15% sulfuric acid, 18.4% sodium sulfate, 3.5% zinc sulfate and 35 p.p.m. lauryl pyridinium chloride. The temperature of the bath was maintained at 68° C.

The filaments extruded through the spinneret were fed 70 into a two-diameter tube having a first portion with an inside diameter of 21 mm. extending for a length of 500 mm. and a second portion with an inside diameter of 27 mm. extending for a length of 240 mm., with a transition section of 60 mm. length connecting these two 75

portions. The acid level before spinning in was maintained at approximately 60 mm. above the center of the tube at the entrance end and approximately 14.75 mm. above the center of the tube at the discharge end. During spinning, this level was lowered slightly due to the pumping action of the yarn traveling through the tube. The yarn was drawn by a first godet through the tube at a rate of 39.4 meters/minute and led to a hot water bath. By the combined pumping action of the yarn, as stated above, and the slight liquid head in the spinbath, acid was forced through the small diameter portion of the tube at a rate of 35.5 meters/minute and through the large diameter portion at a rate of 21.5 meters/minute. From the hot water bath the yarn was passed around a second godet traveling at a peripheral speed of approximately 75 meters/minute so as to impart a stretch of approximately 90% to the yarn. The stretched yarn was collected in cake form in a bucket and aftertreated in known manner. The tenacity of the yarn produced was 432 grams/100 denier and the percent elongation of slashed singles was 10.8.

The face of the spinneret was positioned approximately 21 mm. from the trumpet shaped entrance end of the spinning tube. Upon spinning in, filaments emerging from the spinneret were led into the entrance end of and through the tube by the acid which was caused to flow therethrough by virtue of the liquid head discussed above.

As pointed out hereinbefore, the discharge end of tube 13 projects through a suitable opening provided in wall 23 of chimney 14 and rests against projection 34 of tube extension 30. The yarn and acid bath pass from the tube into trough 33, as can be seen from the drawings. In order to dispose of excess acid and prevent turbulence, the ledge 31 of tube extension 30 extends parallel with but approximately $\frac{1}{16}$ " below the path of yarn travel, thus permitting a small portion of the acid to spill over the ledge and drain down plate 37 through opening 38 into the vertical compartment defined by chimney 14. The remainder of acid travels with the yarn down trough 33 to guide roller 36, at which point the yarn is deflected upwardly from the path of flowing acid with a minimum of turbulence. This portion of acid thereafter also drains down baffle plate 37 into the compartment below, after which it may be reclaimed and recirculated in a manner described supra.

It has been found that a $\frac{1}{16}$ " differential between the height of ledge 31 and the yarn path, as explained herein, maintains the level of acid flowing through trough 33 at a height substantially equal to the apex of the groove on the lower side of roller 36 and thus prevents the building up of this acid level between the roller and discharge end of tube 13, which would result in a turbulent flow of acid producing filament breaks and entanglements with the roller. The yarn remains immersed in a body of smoothly flowing acid, however, until the same is deflected by guide

roller 36. It will be evident from the foregoing that the acid flows in a direction co-current with the yarn until the yarn is suddenly deflected or separated therefrom by the guide roller.

5 By the use of the above-described device it was found that high tenacity viscose yarn could be produced at high spinning speeds. This was due to the manner in which the freshly extruded yarn and spinbath were drawn through the confined treating zone and to the manner in 10 which the yarn was separated from the spinbath with a minimum of turbulence. Moreover, that portion of the spinbath flowing into the vertical compartment defined by the chimney was dispersed uniformly over the baffle plate, which prevented the formation and subsequent rise 15 of foam in this compartment and contributed to a more uniform circulation of the spinbath solution. Additionally, it was found that by the use of the tube extension described herein, the treating tube could be more easily and quickly positioned with respect to the spinneret, resulting in a considerable saving of time with respect to a complete spinning machine of the tube type.

20 It is understood that the foregoing description is for purposes of illustration only and is not intended to limit the scope of this invention except to the extent defined in 25 the following claims.

What is claimed is:

1. A tube extension comprising an elongated supporting plate, a pair of ledges extending longitudinally of said plate and forming thereon a trough, a baffle extending 30 outwardly of said supporting plate in general alignment therewith but inclined with respect to the trough formed by said pair of ledges, and a guide roller secured to one of said ledges and extending into general vertical alignment with said trough, the lower peripheral surface of said 35 guide roller being disposed slightly above the upper edges of said ledges.
2. A tube extension as set forth in claim 1 and further comprising means projecting into said trough adjacent an end thereof opposite said baffle and forming a stop for 40 positioning a tube with respect thereto.
